CLAIM

What is claimed is the ornamental design for a tire, as shown and described.

DESCRIPTION

FIG. 1 is a front right top perspective view of a tire showing my new design;

FIG. 2 is a front elevational view thereof, the opposite side being a mirror image; and,

FIG. 3 is a right elevational view thereof, the opposite side being a mirror image.

The broken line portion of the figure drawings is included to show unclaimed subject matter only and forms no part of the claimed design.
